UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

1ST AVAILABLE COPY

MATRIX-SETTING AND TYPE-LINE-CASTING MACHINE.

1,067,590.

Specification of Letters Patent.

Patented July 15, 1913.

Application filed July 14, 1910. Serial No. 571,934.

To all whom it may concern:

Be it known that I, HEINRICH DEGENER, residing at 26 Hollmannstrasse, Berlin, German Empire, manager, having invented certain new and useful Improvements in or Relating to Matrix-Setting and Type-Line-Casting Machines, do hereby declare that the following is an exact specification of the same.

10 In devices hitherto known on Mergenthaler's machines for setting mixed copy, the matrices to be added to the lines, were collected at different levels by a switch-like rail arranged at the matrix inlet point, allowing the matrix to fall, according to the position of the switch, on to the upper or on to the lower of the two bars or rails arranged in the collecting elevator. All these devices have the disadvantage that the matrices sometimes fall high, and sometimes low, and consequently the "collector" star does not always seize the matrices in the favorable position. In other devices in which the collector star always seizes the 20 matrices at the same point, it is necessary, in changing from one kind of type to another, to change the position of the whole collector carriage or of the star wheel, which again necessitates a complicated change of 25 the whole collector device.

30 This invention makes it possible to seize the matrices always at the same level, so that the star wheel seizes the matrix always at the same level of the matrix, without it being necessary to make an adjustment of the star wheel or of the whole collector carriage.

35 Three constructions according to this invention are illustrated in the accompanying drawings, in which—

40 Figure 1 shows the first construction in front elevation. Fig. 2 is a side elevation of the same, Fig. 3 a front elevation of the second construction, Fig. 4 a plan of the same, and Figs. 5 and 6 show the third construction in front elevation and plan. Figs. 7-12 show two further developments of the 45 constructions shown in Figs. 1-6, namely Fig. 7 is an elevation of the collector carriage, partly in section, Fig. 8 is a corresponding plan, Figs. 9 and 10 are similar

sections through the front portion of the collector carriage, and Figs. 11-13 show the same with a slightly modified construction of the seizing or catching blocks.

55

The collector carriage 1 is generally constructed in the known manner. Ledges 2 and 3 for holding the matrices at the different levels, are arranged on the inside. In the drawing, there are shown two such 60 ledges as required for a machine with two kinds of type and in the event of a greater number of types being employed, the number of ledges is correspondingly larger. The ledges 2, 3 can be fixed and made in one 65 piece with the collector carriage. A little away from the catching or receiving point the upper ledge 2 is provided with a gap into which is inserted a withdrawable piece of rail 5 provided with a handle 4. Behind the gap, the upper rail or bar has a sharpened end 30 as shown in Figs. 1, 3 and 5.

75

The matrices which fall into the collector carriage, always strike the front end of the upper ledge, they are therefore caught all at the same level, seized by the star wheel and pushed forward. When the adjustable bar is in its advanced position, it forms a kind of bridge over which the matrices slide, so that the whole line is collected in 80 the upper position. When the bar is withdrawn, the matrices, as soon as they have passed over the front short pieces of the upper ledge, fall down the gap and arrive at the lower position by coming to rest on 85 the ledge 3. If a matrix should accidentally not fall sufficiently deep, it is drawn downward positively by the beveled portion of the ledge 2 behind the gap, which acts on the upper edge of the matrix lug.

90

In order to bring into the lower position, the matrices which stand on the fixed short piece of the ledge 2 in front of the gap, (in case they are to be brought into casting position with the upper characters), the machine is provided with a curved part 6 projecting into the path of the collector carriage rising upward, the said part acting on the matrices during the rising of the collector carriage, so that they are positively 100 pushed to the left to such an extent as to enable them to fall into the lower position

95

through the gap. Moreover, the holding finger can also be provided with a spring part 7 which becomes operative and forces the matrices into the lower position, if the 5 matrices brought above the gap by the curved guide, adhere together owing to friction or the like, and do not fall down by gravity. Although the curved part 6 and the spring part 7 are shown only in Fig. 1, 10 it will be obvious that when applicable they may be employed in connection with other forms also, that is to say, whenever it is deemed necessary to move the matrices inward in the collecting elevator, or if it be 15 desirable to move positively downward matrices which are improperly maintained in an elevated or abnormal position by adhesion, etc.

As will be seen from Figs. 3 and 4, the 20 gap in the upper ledge can be obtained, by another method which consists in dividing the upper ledge into two portions 8 and 9, of which the front portion 8 is fixed, while the second one, constituted by the bar 9, is 25 longitudinally adjustable. When the bar 9 has been moved close to the part 8, the matrices come into line on the same, and if the bar is pushed to the left, so that a gap is produced between the parts 8 and 9, the matrices 30 fall through at that point and arrive at the lower position. In this case, in the same way, as in the first construction, the right hand end of the bar 9; as shown in Fig. 3, can be beveled. As it is possible to 35 shift the bar 9 at will to a greater or less extent, each single matrix or even whole words can be brought at will into the lower position. In this construction, the bar 9, when it is in its right hand position, that 40 is to say, when there is no gap, would be flush with the left hand end of the collector carriage, while in its left hand position it would project beyond the end of the collector carriage, so that it would interfere with 45 the other parts of the machine when the collector is moved in vertical direction. In order to prevent it, the bar 9, adjustable in the longitudinal direction, is arranged as shown in Figs. 11 and 12, so that when it 50 is brought into its left hand position, and the gap through which the matrices fall is formed between it and the fixed part 8, it is flush with its left hand lateral edge with the collector carriage. When, however, it is 55 pushed to the right, so that it adjoins the fixed part, a portion remains free on the left hand side of the collector. In order to secure the matrices at this portion of the 60 collector against falling down, the back of the collector is provided with a short piece of bar 15 which is arranged at the same level as the bar 9, and is preferably sharpened in front in order to enable the matrices to be brought on the same.

65 In the construction shown in Figs. 5 and 6,

the front ledges are not made adjustable at all. The upper ledge is provided with a gap, that is to say, it consists of two separate parts 8 and 27 between which is left a space, and of which the part 27 is again provided 70 at its right hand end with the above mentioned bevel. The matrices which fall on the ledge 8 would, therefore, slide through the gap during further movement and reach the lower position. In order to enable them to be collected also in the upper position, an adjustable bridge 10 is mounted on the back of the collector carriage. When the bridge 10 is in the advanced position, it guides over the bridge, the matrices which come 80 to rest on the bridge with their foot edge on the side farthest away from the compositor, so that they reach the ledge 27. When the bridge 10 is withdrawn, the matrices all reach the bottom position in the 85 manner already described. In case of more than two kinds of type, all the ledges, except the bottom one, must be provided with gaps in the manner shown, which must be adapted to be bridged over for the purpose 90 stated.

Figs. 7-13 show, by way of example, devices for bringing the matrices which stand on the fixed catching or receiving part, if necessary into the lower position. In the 95 arrangement previously described, it may happen that the matrices, struck by the curved part, will take up an oblique position and sometimes slide out altogether from the collector carriage. The first arrangement for avoiding this disadvantage is as follows: For catching the matrices there are provided two bars 11 which can be secured in any desired manner to the machine frame. On one side of the collector carriage, (in the drawing on the front side), is arranged a slide 12, the upper edge of which is in the plane of the upper edge of the collecting bars 11. The slide 12 is pressed by a spring 13 into the collector carriage. In its 100 withdrawn position, it is held by a projection 14 of the transversely adjustable bar 9 engaging with a slot provided on its surface. When the bar is in the position shown in Figs. 8 and 9, all the matrices will then 105 reach the lower position in the known manner, as they fall into the lower position through the gap produced between the bar 9 and the catching bars 11. The matrices standing on the bars 11 themselves, will also 110 reach the lower position, for, as these bars are fixed to the machine frame, the matrices standing on the same will lose their point of support as soon as the collector carriage moves upward without the said bars 11. In 115 order to prevent the matrices in that case from falling out altogether, a bar 16 is arranged on one or on both lateral walls, in a fixed or a springy manner, at such a level 120 that the matrices striking into the lower po- 125

sition, rest on them with the lower edge of their upper lugs. When ordinary type is being set and all the matrices must reach the lower position, the matrices standing on the bars 11 will, therefore, lose their support and become suspended with their upper lugs on the bar 16. Instead of the bar 16 a spring 17 could also be arranged mounted on the back of the collector carriage at such a level that it supplements the fixed ledge at the beginning of the collector carriage. If the collector carriage is in the collecting position, the spring 17 will be forced by the back catching or receiving bar 11, as shown in Fig. 10, into a recess of the collector carriage, but if, owing to the raising of the collector carriage, the spring 17 is released, it will come under the matrices, at the level of the bottom ledge, so that the matrices standing on the receiving bars, will rest with their back lugs on the spring 17. When the matrices are to remain in the upper position, that is to say, when distinctive type or italics are being set, the bar 9 is in its right hand position, and consequently the recess 18 of the bar projection enables the slide 12 to move forward; at first however, only to the extent allowed by the bevel 19 of one receiving bar. The slide then engages a little under the matrices themselves. If the collector carriage then rises, the slide 12 will be able to come forward to the same extent to which it is released from the receiving bars. The matrices consequently get a support on the slide, and cannot fall into the lower position. The travel of the slide is limited by striking the projection of the bar 9. The place of the slide 12 can be taken by a pawl 20 which is preferably made in the shape of a bell crank lever and is operated by a pin 21 which again is controlled by a curved part 22 mounted on the movable bar 9. When the bar 9 is in the right hand position, so that the matrices are cast in the upper position, the pin 21 can move upward, consequently the pawl 20 can come under the matrices in the same manner as explained before for the slide 12.

Figs. 11-13 show a third construction of the receiving block. In this construction, the holding of the matrices in their upper position, in the same way as in the constructions shown in Figs. 1-4, is effected by a transversely adjustable bar 9 which, in its left hand position, leaves a gap between it and the receiving block, so that the matrices, in passing over the said gap reach their bottom position in the manner described. For catching or receiving the matrices themselves, the slide 31 is used which in this case is operated by means of a double lever 25. A spring 23 has the tendency to withdraw the slide 31 from the path of the matrices. On the frame of the machine a fixed stop 24 is provided with an oblique surface. When the collector reaches its lower position in which it catches the matrices, the free arm of the double lever 25 will slide along the oblique surface of the stop 24, so that the double lever will be turned, and the slide 31 advanced. If, however, the collector is raised, the spring 23 will be able to withdraw the slide 31. In order that the matrices may be caught at both lugs, a second catching or receiving block 26 may be arranged and firmly secured to the frame of the machine. If the matrices are to be cast in their lower position, the bar 9 will be in the position shown in Fig. 12. The matrices are first caught in the collector in the upper position by the slide 31 and the block 26, and after having passed beyond these two parts, fall through the gap on to the lower ledge 3 on which they remain. Those matrices which, after the completion of the line, are still standing on the block 26 or on the slide 31, fall into their lower position as soon as the collector is raised, as the bar 26 is secured to the frame of the machine, and consequently does not participate in the upward movement of the collector, and the slide 31 is withdrawn owing to the action of the spring 23. If the matrices are to remain in their upper position, the bar 9 is pushed to the right, and the gap thus closed, this results in a projection 28 arranged laterally on the bar engaging simultaneously with a recess 29 of the slide 31 and locking the latter. If the collector is then moved upward, the spring 23 can no longer withdraw the locked slide 31, the latter consequently remains in the advanced position, and thus holds the foremost matrices in their upper position.

Having now particularly described and ascertained the nature of my invention and in what manner the same is to be performed, I declare that what I claim is:

1. In a matrix setting and type line casting machine of the Mergenthaler type a collecting elevator containing in combination rails for holding the matrices in different levels the upper rail consisting of two parts separated from each other by a gap and means for bridging said gap.
2. In a matrix setting and type line casting machine of the Mergenthaler type a collecting elevator containing in combination rails for holding the matrices in different levels, a stop catching the matrices all in their uppermost position and forming a continuation of the upper rail, the upper rail being separated from the stop by a gap and means for bridging said gap.
3. In a matrix setting and type line casting machine of the Mergenthaler type a collecting elevator containing in combination rails for holding the matrices in different levels, the upper rail consisting of two parts separated from each other by a gap and

- one part being adjustable for bridging said gap.
4. In a matrix setting and type line casting machine of the Mergenthaler type a collecting elevator containing rails for holding the matrices in different levels, the upper rail consisting of two parts separable from each other by a gap, the front portion being fixed to catch the matrices and the second part being longitudinally adjustable.
5. In a matrix setting and type line casting machine of the Mergenthaler type a collecting elevator containing in combination rails for holding the matrices in different levels, the upper rail consisting of two parts separable from each other by a gap, the front portion being fixed to catch the matrices and the second part being longitudinally adjustable and means for moving the adjustable part.
6. In a matrix setting and type line casting machine of the Mergenthaler type a collecting elevator containing rails for holding the matrices in different levels, the upper rail consisting of two parts separable from each other by a gap, the part situated behind the gap being beveled on the bottom of the right hand end.
7. In a matrix setting and type line casting machine of the Mergenthaler type in combination a collecting elevator containing rails for holding the matrices in different levels, the upper rail consisting of two parts separable from each other by a gap and a curved part projecting into the path of the collecting elevator, said curved part pushing the matrix line to the left.
8. In a matrix setting and type line casting machine of the Mergenthaler type in combination a collecting elevator containing rails for holding the matrices in different levels, the upper rail consisting of two parts separable from each other by a gap and a curved part projecting into the path of the collecting elevator, said curved part pushing the matrix line so far to the left that no matrix stands upon the adjacent part of the upper rail.
9. In a matrix setting and type line casting machine of the Mergenthaler type in combination a collecting elevator containing rails for holding the matrices in different levels, the upper rail consisting of two parts separable from each other by a gap, a curved part projecting into the path of the collecting elevator, said curved part pushing the matrix line so far to the left that no matrix stands upon the adjacent part of the upper rail and a spring member arranged over the curved part and acting on the matrices.
10. In a matrix setting and type line casting machine of the Mergenthaler type a collecting elevator containing in combination rails for holding the matrices in different levels, a stop catching the matrices all in their uppermost position and forming a continuation of the upper rail, the upper rail being separable from the stop by a gap, said stop being secured to the machine frame.
11. In a matrix setting and type line casting machine of the Mergenthaler type a collecting elevator containing in combination rails for holding the matrices in different levels, a stop catching the matrices all in their uppermost position, forming a continuation of the upper rail and being secured to the machine frame, the upper rail being separable from the stop by a gap, means for bridging said gap and means for holding the matrices to be cast in the lower position standing on the stop and losing their support during the upward movement of the collecting elevator, in their lower position.
12. In a matrix setting and type line casting machine of the Mergenthaler type a collecting elevator containing in combination rails for holding the matrices in different levels, a stop catching the matrices all in their uppermost position, forming a continuation of the upper rail and being secured to the machine frame, the upper rail being separable from the stop by a gap, means for bridging said gap and means for holding the matrices to be cast in the lower position, standing on the stop and losing their support during the upward movement of the collecting elevator, in their lower position, said means supporting the lugs of the said matrices.
13. In a matrix setting and type line casting machine of the Mergenthaler type a collecting elevator containing in combination rails for holding the matrices in different levels, a stop catching the matrices all in their uppermost position, forming a continuation of the upper rail and being secured to the machine frame, the upper rail being separable from the stop by a gap, means for bridging said gap and means for holding the matrices to be cast in the upper position standing on the stop, in their upper position.
14. In a matrix setting and type line casting machine of the Mergenthaler type a collecting elevator containing in combination rails for holding the matrices in different levels, a stop catching the matrices all in their uppermost position, forming a continuation of the upper rail and being secured to the machine frame, the upper rail being separable from the stop by a gap, means for bridging said gap and means for holding the matrices to be cast in the upper position standing on the stop, in their upper position, said means being controlled by the means for bridging the gap.
15. In a matrix setting and type line cast-

ing machine of the Mergenthaler type a collecting elevator containing in combination rails for holding the matrices in different levels the upper rail consisting of two parts separable by a gap, one part being arranged to catch the matrices and the second part being longitudinally adjustable to close the gap, said second part being flush with the end of the collector when in its outward position, that is to say, when there is a gap and an opposing rail piece arranged at the same level as the said second part.

16. In a typographical machine, the collecting elevator provided with means for sustaining the matrices in elevated position, the said means being arranged so that an interior gap may be formed through said means to permit the descent of the matrices to a lower level.

20 17. In a typographical machine, the collecting elevator provided with means for sustaining the matrices at different levels, the upper one of the said means being arranged so that an interior gap may be formed through said means to permit the de-

scent of the matrices to a lower one of the said means.

18. In a typographical composing machine, the collecting elevator provided with a rail for sustaining the matrices in elevated position, the said rail being formed in two separable sections to permit the passage of the matrices therebetween.

19. In a typographical machine, the combination of the collecting elevator for the matrices with an abutment located in its path to engage the sides of the matrices and move them inwardly therein.

20. In a typographical machine, the combination of the collecting elevator for the matrices with a yielding member located in its path to engage the tops of the matrices and seat them therein.

In witness whereof I have hereunder set my hand in presence of two witnesses.

HEINRICH DEGENER.
